DESIGN FOR A VELOCIPED

Bert J. Anderson, Hammond, Ind.

Application April 16, 1934, Serial No. 51,425

Term of patent 7 years

To all whom it may concern:

Be it known that I, BERT J. ANDERSON, a citizen of the United States, residing at Hammond, in the county of Lake and State of Indiana, have invented a new, original, and ornamental Design for a Velocipede, of which the following is a specification, reference being had to the accompanying drawing, forming part thereof.

The drawing is a perspective view of the veloc-

ipede of this design and shows in particular the wide streamlined handlebars, the drop side fender partially covering the fork and front wheel, and the streamlined fenders covering a part of the frame and rear wheels.

I claim:

The ornamental design for a velocipede, substantially as shown and described.

BERT J. ANDERSON.
